UNITED STATES PATENT OFFICE.

BELDEN D. JONES, OF CHICAGO, ILLINOIS, ASSIGNOR TO CAMEL COMPANY, OF CHICAGO, ILLINOIS, A CORPORATION OF MAINE.

CAR STRUCTURE.

1,114,060.

Specification of Letters Patent.

Patented Oct. 20, 1914.

Substitute for application Serial No. 706,967, filed July 1, 1912. This application filed May 22, 1914. Serial No. 840,167.

To all whom it may concern:

Be it known that I, BELDEN D. JONES, a citizen of the United States, residing in the city of Chicago, county of Cook, and State of Illinois, have invented certain new and useful Improvements in Car Structures, of which the following is a specification.

This invention relates to improvements in car structures and more particularly to the door openings in such structures and the means for mounting the door to close such openings.

Among the salient objects of the invention are to provide in a construction of the type above mentioned a door offset from the main side wall of the car; to utilize a constituent element of the car structure to close the upper end of the offset door openings; to provide a construction in which the door is supported and confined adjacent the outer edge of the offset door openings; to insure a weatherproof joint at the upper end of the door opening; to secure the above advantages by a construction which will permit of the use of commercial forms of metallic bars; and in general to provide an improved construction of the character referred to which may be economically manufactured and readily assembled.

The invention further resides in various features of construction and combinations of parts hereinafter disclosed.

In the drawing, Figure 1 is a fragmentary side elevation showing my invention applied to a freight car. Fig. 2 is an enlarged fragmentary horizontal section partly broken away. Fig. 3 is an enlarged fragmentary vertical section of the car and door partly broken away intermediate the top and bottom portions thereof.

Referring first to the general construction of the freight car as shown in the drawings, it will be noticed that 1 designates the car as a whole, 2 the outer metallic framing, on the inner side of which is positioned the usual sheathing 3; 4 designates the roofing, 5 the flooring, and 6 the door opening. At each side of the door opening are wooden posts 7 and 8,—the parts above mentioned

being of the usual construction. The posts 50 7 and 8 are however offset outwardly and co-operating therewith are metallic members 9 and 10, these being preferably formed of commercially rolled Z bars fastened both to the door posts and the car sides. 55

That portion of the floor which is positioned intermediate the posts 7 and 8 extends outward beyond the car sides a short distance, and this extension is supported by a sill member 11 extending along the 60 car side beneath the flooring extension. The upper surface of this extension is provided with a guard plate 12 which has a downwardly turned flange 12' forming a protection for the end of the flooring. The guard 65 plate 12 and sill 11 are riveted or otherwise secured together as shown in Fig. 3. The upper portion of this offset space is covered by plate 12'' which may be of any desired configuration but is preferably 70 formed as a part of the upper side plate 13. In the particular construction disclosed in the drawings, this side plate is of Z bar construction, and is arranged with its parallel webs extending in horizontal planes, 75 and its central web is positioned substantially in the vertical plane of the car side. Upon the upper horizontal web 13' of the side plate 13 is positioned the roof 4 which is secured thereto by means of bolts 15 which 80 extend through filler members 4'. As shown in Fig. 3 the roof is provided with metallic plates having downwardly projecting marginal portions 14' which are secured by means of rivets 14 to the vertical web of 85 the side plate 13. The arrangement above defined will prevent any moisture passing over the top of the side plate 13 into the car, and the integral lower horizontal flange 12'' which extends over the door opening 90 extension, provides a guard for the upper end of this portion.

It is necessary that the door for closing the projected door opening be so mounted that while it will effectively prevent any rain 95 or other moisture from entering the interior of the car, it will nevertheless be easily moved back and forward on its track. I

secure this result preferably by the following arrangement of parts. A track member 16 is formed of a Z bar having parallel horizontal flanges 20 and 18, and a connecting vertical flange 19. The upper horizontal flange of the bar 16 is positioned adjacent to the lower horizontal flange 12" of the side plate 13 and is secured thereto by rivet 17, though it is obvious that this flange 10 could be welded or otherwise fastened together. The door 22 is provided at its upper end with a plurality of wheels 21 mounted on rollers 23 journaled on suitable brackets 24 which are bolted as shown at 25 to the 15 outer face of the door. These wheels run upon a track which comprises the lower horizontal flange 18 of the Z bar 16. It will be noticed that this Z bar 16 has its vertical flange 19 positioned outward a slight distance from the plane of the outer edge of the door opening, and in the space thus formed there extends a vertical flange 26 which co-operates with the vertical flange 19 of the Z bar 16 to prevent the wheel 21 20 from leaving its track 18. This vertical flange 26 is preferably a part of a Z bar 27 fastened at the upper edge of the door to form a suitable guard therefor.

The arrangement of parts as above defined 30 effectively prevents the passing of any water into either the car or the door opening space as follows: Any water falling upon that portion of the roof inside of the plane of the car side will be effectively carried off by the 35 roof itself, and inasmuch as the top of the door opening space is guarded by the flange 12" of the Z bar 13 which is in turn protected by the down-turned edges of the roofing sheets, no water can pass into the car at this point. Any moisture falling upon the 40 wheel or its track 18 is prevented from passing into door opening space, by means of the vertical flange 21 which extends upward a considerable distance beyond the 45 plane of the track. The wheel is thus not only prevented from lateral displacement from its track but the same elements serve to prevent any moisture passing to the inside of the car.

50 Means are also provided for preventing any passage of water or other moisture through the vertical edges of the door structure. The door post guard 9 has secured thereto a flat metal plate 31, slightly spaced 55 away from the central flange of the Z shaped member 9 by a suitable spacer 31'. This forms an open ended vertical extending channel 32 at one side of the door opening. The plate 31 is extended outwardly beyond 60 the edge of the door opening, and has its outer end 33 positioned in the path of the movement of the door 22, forming a door stop. Any moisture which leaks through the end of the door and the stop 33 will pass

into the open ended channel 32 and be 65 drained off to the ground.

Means are also provided for preventing any moisture from entering the car at the opposite end of the door opening, namely; that adjacent the door post 8 and its guard 70 10. It is necessary, however, that such moisture preventing means does not interfere with the sliding of the door beyond the door post as would clearly be the case if a stop were employed similar to the stop 33 75 at the opposite end of the door. An angle iron 34 has one end of its angle, such as 35, bolted to the outer face of the door and its opposite end 37 bent around the corner of the door substantially parallel with the 80 end thereof. The end 37' of the flange 37 of the angle bar extends inward a slight distance beyond the plane of the inside face of the door. It is to be noticed, however, that the flange 37 is spaced from the end of 85 the door to form a drainage opening 38. The space between the inner end 37' of the flange 37 and the Z bar guard 10 is however sealed by a hook shaped extension 39' carried by the plate 39 which is bolted to the 90 web of the Z bar 10. Any water therefore leaking past the joint between the ends of the plate 39 and the flange 37 will pass into the drainage space 38 and be discharged at the lower end of such space. 95

It will be obvious from the foregoing description that the door is spaced a considerable distance from the plane of the car side, and that this desired result is obtained without additional supporting members. While 100 I have shown the Z bar 16 secured to the roof-supporting side plate of the car, it is obvious that it might be carried by a bar not performing the roof-supporting functions. However, the utilizing of the side 105 plate as shown not only avoids the use of additional members but insures that the upper end of the supporting member will be adequately protected from moisture passing therethrough. 110

I claim:

1. The combination with a car body provided with a door opening positioned outward beyond the plane of the car side and a door adapted to be moved across said opening, of a track for supporting said door at its upper end, comprising a Z bar having its parallel bars horizontally arranged and its central bar arranged vertically, said door having a vertically extending bar positioned inside of the vertical portion of said Z bar and co-operating therewith to prevent lateral movement of the door. 115

2. The combination with a car body having a Z bar side plate arranged with its 120 central web extending vertically substantially in the plane of the car side and its upper web extending inward beyond said 125

plane and its lower web extending horizontally outward beyond the plane of the car side, of a door opening having the lower horizontal web of the car plate closing its upper edge, a door for closing said opening, said door having a roller at its upper end, and a track for supporting said roller com-

prising a Z bar having its upper horizontal flange secured to the lower horizontal flange of said side plate.
